UNITED STATES PATENT OFFICE.

JOHN N. RICE, OF NEW CASTLE, PENNSYLVANIA.

DUMPING-CAR.

SPECIFICATION forming part of Letters Patent No. 259,585, dated June 13, 1882.

Application filed April 21, 1882. (No model.)

To all whom it may concern:

Be it known that I, JOHN N. RICE, of New Castle, in the county of Lawrence and State of Pennsylvania, have invented certain new and useful Improvements in Dumping-Cars; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal vertical section of my improved dumping-car. Fig. 2 is a plan of the under side of the car-body. Fig. 3 is a plan or top view of the truck-platform, and Figs. 4, 5, and 6 are detail views of the axle-box.

Similar letters of reference indicate corresponding parts in all the figures.

My invention contemplates an improved construction of dumping-cars for dumping coal, gravel, or ballast on railroads, as herein-after more fully described, and particularly pointed out in the claims.

In the accompanying drawings, A A are the sides or sills of the truck frame or platform, which are connected by end timbers, B B, to which draw-heads may be secured.

C is a bridge or platform, which has a centrally-perforated bearing-plate, D, and a circle, E, of iron or other suitable metal. Upon this circle rests the circle E' of the rotary base F of the car-body, (shown at G,) which is hinged to one end of the box or base F by a detachable hinge-rod, H. At the opposite end of the base is a catch or key, I, which engages with a link, K, secured upon the end of the car-body. The latter is so placed upon its rotary

base or box F that the preponderance of weight will be over the base, the hinge H being a little to one side of the middle line of the bed of the car-body, as shown clearly in Fig. 1. This permits the car-body to be readily tilted with its load, (after the link K and latch I have been disengaged,) so as to drop or dump the load at any desired place on the track, the end-gate, G', being of course first removed.

The car-body G rests with its bottom upon

two transverse parallel beams g g, and when 50 it is desired to use the car for ordinary transportation purposes the hinge-rod H may be unshipped and the body placed evenly or midway upon its hollow box or base F, with the timbers g g supported by the sides of box F. 55

The rotary box or base F is held upon platform C by a center bolt, L, so that the car-body may readily be swung to either side before dropping the load. In carrying heavy loads the box F may be suitably ballasted with 60 stones or pig-iron to prevent it from tilting on its platform C when the car-body is dumped. This is an important feature, because it relieves the truck-timbers of uneven and undue strain, and prevents the truck from tilting on 65 the track when the load is upset sidewise.

The axle-boxes (shown at M) are of cast-iron, and have side wings or flanges, m m, which fit into slotted side pieces, n n, of the journal-bearings N. They are held in place by pins 70 or bolts o, inserted through ears O, which project from the side sills, A A, above the journal-bearings N, the front side of the box being cast with a plate or guard, m', which extends up above the side flanges, m m, and against 75 which pin o rests. This guard-plate effectually prevents dirt from entering the axle-boxes in dropping or dumping the load, as it is very apt to do in this class of cars, especially in dumping the load sidewise over the boxes, as 80 in raising the car-body from its tilted position dirt adhering to it is apt to drop into the boxes, which in cars of this class cannot well be made of the more expensive dirt-excluding patterns used for passenger-coaches. By placing a little waste saturated with tallow or lubricating-oil in the box the axle will run smoothly and easily for a long time.

Having thus described my invention, I claim and desire to secure by Letters Patent of the 90 United States—

1. In a dumping-car, the combination, with the truck A, having platform C, provided with the circle E, of the box or hollow base F, adapted to form a receptacle for ballast, and provided with the circle E', center bolt, L, and hinged car-body G, substantially as described, for the purpose set forth.

2. In a dumping-car, the combination of the side sills, A, having the projecting ears O and slotted journal-bearings N, arranged on opposite sides thereof, detachable boxes M, 5 having laterally-projecting wings or flanges m and shield or guard plate m', and detachable pin or bolt o, inserted through the part O and bearing against the guard-plate m', all constructed and combined substantially as and 10 for the purpose herein shown and specified.

In testimony that I claim the foregoing as my own I have hereunto affixed my signature in presence of two witnesses.

JOHN N. RICE.
